(57) **CLAIM**

The ornamental design for a vehicle mirror, as shown and described.

DESCRIPTION

FIG. 1 is a perspective view of a vehicle mirror showing an embodiment of the design of the invention.

FIG. 2 is a rear view thereof.

FIG. 3 is a front view thereof.

FIG. 4 is a bottom view thereof.

FIG. 5 is a top view thereof.

FIG. 6 is a side view thereof.

FIG. 7 is an opposite side view thereof; and,

FIG. 8 is a perspective view of the vehicle mirror of FIGS. 1-7, showing the vehicle mirror in use, and with the tool portion removed.

The broken lines showing portions of the vehicle mirror, form no part of the claimed design. The broken lines illustrating a motorcycle, in FIG. 8, depict environmental structure that forms no part of the claimed design.
